UNITED STATES PATENT OFFICE.

ARMAND H. PEYCKE, OF CHICAGO, ILLINOIS, ASSIGNOR TO AMERICAN STEEL FOUNDRIES, OF CHICAGO, ILLINOIS, A CORPORATION OF NEW JERSEY.

Brake Supporting and Releasing Arrangement.

1,315,401.

Specification of Letters Patent.

Patented Sept. 9, 1919.

Application filed April 22, 1918. Serial No. 229,936.

To all whom it may concern:

Be it known that I, ARMAND H. PEYCKE, a citizen of the United States, residing at Chicago, in the county of Cook and State 5 of Illinois, have invented certain new and useful Improvements in Brake Supporting and Releasing Arrangements, of which the following is a specification.

This invention relates to brake supporting 10 and releasing arrangements.

One of the objects of this invention is to improve and simplify in a novel manner, means for supporting and releasing brakes.

Another object is to provide novel brake 15 supporting and releasing mechanism adapted to meet the requirements for successful commercial operation.

Generally speaking these and other objects are accomplished by providing in brake 20 mechanism the combination of a plurality of brake beams, a support, and means whereby said beams are supported by said support.

The invention is illustrated on the accompanying sheets of drawings in which—

Figure 1 is a fragmentary side elevation of brake mechanism, embodying my invention.

Figs. 2, 3, 4, 5 and 6 are fragmentary side 30 elevations of brake supporting and releasing means, forming modifications of my invention.

The various novel features of my invention will be apparent from the following description and drawings.

Referring first to Fig. 1 of the drawings, it will be noted that I have shown my invention in connection with a railway car truck including a spring plank 10 to which is secured a spring plate member 11, which extends upwardly and laterally with respect to the spring plank and terminates in a flat portion 12 to which is riveted a rigid supporting member 13 to the opposite ends of 40 which hangers 14 are pivotally connected at points 15. Pivotally connected at the lower ends of each of the hangers 14 is a fulcrum 16, connected to a brake beam 17. It will be noted that these brake beams are 45 located upon opposite sides of a pair of wheels carried by an axle 18. Connected to an intermediate point of the supporting member 13 and preferably over the center of the axle, is a double release spring 19, the 50 opposite portions 20 of which preferably ex-

tend downwardly and then loop upwardly with their free ends 21 slidably engaging the inner faces of the brake beam 17. This double spring 19 has for its function the releasing of the brakes when the releasing 60 pressure has ceased to be exerted. By means of this arrangement balance hangers 14 and release springs 19 are supported in a simple manner by a single balance hanger bracket 11, secured to the spring plank 10. 65

Referring to Fig. 2 of the drawing, it will be noted that an angle or channel bracket member 22 is provided which is connected to the spring plank 10 and has at its outer end a rolled up portion 23 for the reception 70 of a pivot pin 24 upon which the upper central portion of the double release spring 25 is connected. This double release spring extends downwardly and then loops upwardly and is pivotally connected at 26 to 75 brake beam fulcrums 27—27.

In Fig. 4 the supporting member 28, which is connected to the spring plank 10 is preferably of plate material and has its outer portion extending vertically downwardly over the center of the axle 18, the oppositely arranged release springs 29 being secured to the free end of the supporting member 28, said springs first being looped upwardly, then extending downwardly and 85 then looping upwardly again and being pivotally connected at 30 to the brake beam fulcrums 31.

In Fig. 6 of the drawings, the double release spring 32 is supported on a central 90 point 33 and then on opposite sides extends downwardly and loops upwardly and is pivotally connected at 34 to suitable member 35, which is connected to the brake beam 36.

In Fig. 5 is shown an arrangement including a rigid angle or channel member 37, which is connected to the spring plank 10 and extends laterally over the axle 18. Hangers 38 are pivotally connected to the support 37 and are also pivotally connected 95 to brake beam fulcrums 39. The release springs 40, in this modification are secured to the supporting member and extend downwardly, having their lower ends slidably engaging hangers 38.

By referring to Fig. 3, it will be noted that two supporting members 41 and 42 preferably of plate material are secured to each other and to the spring plank 10. One of said supporting members 41 extending upwardly 110

and laterally to the opposite side of the axle 18 and has pivotally connected to its outer end 43, a hanger 44, which is pivotally connected to a brake beam fulcrum 45. The other 5 supporting member 42 extends upwardly and laterally only a short distance and has pivotally connected to its outer end a hanger 46, to the lower end of which is pivotally connected a brake beam fulcrum 47.

10 In the arrangements herein disclosed the brake rigging on opposite sides of each pair of wheels is supported by means extending from and being wholly on one side of the spring plank. Coöperating release springs 15 for releasing the brakes are also shown in operative association with the other parts.

There may be various other modifications 20 of my invention and it is my intention to cover all such modifications which do not involve a departure from the spirit and scope of the following claims.

I claim:—

1. In brake mechanism, the combination 25 of a plurality of oppositely arranged brake beams; a support, balance hangers connected to said support and said beams, and releasing means operatively connected to said support and to each of said brake beams for giving the latter a releasing movement.

2. In brake mechanism, brake beams arranged on opposite sides of a pair of wheels, a spring plank, and means extending from said spring plank for supporting each of said brake beams.

3. In brake mechanism, the combination 35 of a spring plank, a plurality of brake

beams located on one side of said spring plank and on opposite sides of a pair of wheels, and means extending from said spring plank for supporting said brake beams.

40

4. In brake mechanism, the combination of a spring plank, a plurality of brake beams located on one side of said spring plank and on opposite sides of a pair of wheels, and means supported from said 45 spring plank for supporting said brake beams and for giving said brake beams a releasing movement.

50

5. In brake mechanism, the combination of a support, a plurality of brake beams on the same side of said support and on opposite sides of a pair of wheels, a balance hanger bracket extending from said support, and supporting connections from said balance hanger bracket to said brake beams.

55

6. In brake mechanism, the combination of a support, a plurality of brake beams on the same side of said support and on opposite sides of a pair of wheels, a balance hanger bracket extending from said support, supporting connections from said balance hanger bracket to said brake beams, and releasing means connected to said balance hanger bracket and being operatively associated with said brake beams.

60

Signed at Chicago, State of Illinois, this 16th day of April, A. D., 1918.

ARMAND H. PEYCKE.
